METHOD OF RECORDING AND REPRODUCING WAVE FREQUENCIES

Application filed June 18, 1930. Serial No. 462,068.

My invention relates to a new and improved method for recording and reproducing wave frequencies.

A method for electro-magnetically recording telephone or telegraph signals was invented by Valdemar Poulsen in 1898, but with the method described and used by him, and as improved upon from time to time by himself and by others, it is impossible to satisfactorily record and reproduce speech or music which will compare in quality with even the poorest type of modern phonograph. This is due to the fact that the frequencies present in speech and music, as harmonics or overtones, vary between some 20 cycles per second and 16,000 to 18,000 per second, and with his method the lower, and especially the higher frequencies, cannot be efficiently recorded and retained on the magnetizable body used for recording, whether this be a steel wire, tape, disc, cylinder, or other physical shape of magnetizable material.

My invention contemplates a method for recording and reproducing any desired range of wave frequencies, whether it be in the audio-frequency range above mentioned, or above this limit, and which can therefore be used for the recording and reproduction of audible sounds in their true acoustical relation, as well as for recording and reproducing variations in electric current of much higher frequency, such as are present, for instance, in the transmission of a moving picture by means of television apparatus.

In the reproduction from an electro-magnetic record made by the methods followed prior to my invention, a background of rushing sound has been apparent in the reproduced speech or music, similar in character to the "needle scratch" in reproduction from a phonograph, which objectionable feature may be termed "wire scratch". This "wire scratch" arises from two sources:—First, it is introduced at the time of making the electro-magnetic record on the magnetizable body, and, second, it is again produced when reproducing the electro-magnetic record by the means known and used for this purpose prior to the present invention.

In following my method for making a

copy of a phonograph record on a magnetizable body, for instance, the electro-magnetic reproduction of such a copy is clearer and more natural than the reproduction from the original phonograph record by means of an acoustical reproducer; such electro-magnetic reproduction is also of such a tonal quality that it cannot be distinguished from an electric reproduction from the original phonograph record.

If, however, an electro-magnetic record be made on a magnetizable body under my invention, using as the original which is to be recorded, an orchestra, for example, the reproduction of such electro-magnetic record will be better than an electric reproduction of a phonograph record, due to the fact that the above-mentioned "needle scratch" is present in the reproduction from the phonograph, thus introducing an undesirable sound which was absent in the music of the original orchestra. In the reproduction from the electro-magnetic record made and reproduced according to my invention, "wire scratch" is absent and the music as reproduced is an exact duplicate of that played by the orchestra, without the addition or subtraction of any frequencies contained in the original music.

Having outlined some of the advantages and novel features of the present invention, and what can be accomplished by its use, I will now state generally the means that may be employed in the practice of my invention, to accomplish the desired results.

A microphone or telephone transmitter is used to change sound waves in the air into corresponding electric waves in the wires leading from it; similarly, a photo-electric cell is used to transform light waves emanating from an object or picture into electric waves in the wires leading from the photo-electric cell. These electric waves must then be recorded on a magnetizable body, without changing their form, amplitude, or character in any way, and without adding anything to or subtracting anything from them, since any change whatsoever will result in an incorrect copy of the original sound or picture.

In the same way, when reproducing a record so made on a magnetizable body, electric

waves must be produced which are an exact copy or reproduction of the original electric waves coming from the microphone or photoelectric cell, which electric waves are again 5 changed into sound or light waves by a suitable device, such as a loud speaker, etc., to render them audible or visible as an exact copy of the original sound waves or light waves.

10 Any suitable means may be used to transform sound or light waves into corresponding electrical waves, and these electrical waves may be amplified to whatever degree is desired, by means of a suitable amplifier. These 15 electrical waves are then made to energize a system of electro-magnets, setting up a series of magnetic fluctuations in the cores of the electro-magnets, which correspond to the original sound or light waves. These magnetic 20 fluctuations in the above-mentioned cores are impressed on a magnetizable body which is caused to move past the cores, with the result that the magnetic condition of the magnetizable body is altered to correspond 25 to the original sound or light waves.

In the accompanying drawings:

Fig. 1 is a diagrammatic view of means for 30 practicing the method of my invention, and illustrating an apparatus for recording magnetic impulses upon a magnetizable body;

Figs. 2, 3 and 4 are diagrammatic views of a portion of Fig. 1, illustrating modified forms of apparatus;

Fig. 5 is a diagrammatic view of an apparatus 35 employed for reproducing the magnetic record from the magnetizable body;

Fig. 6 is a view similar to Figs. 1 and 5, illustrating the combined recording and reproducing circuits in operative relation with 40 a magnetizable body;

Fig. 7 is a diagrammatic view taken at right angles to the view of Fig. 6, showing an arrangement of apparatus that may be employed for simultaneously recording and reproducing; and

Fig. 8 is a diagrammatic view of means for translating the magnetizable body in operative relationship with respect to a magnetic circuit.

50 Referring to the drawings, and more particularly to Fig. 1, the recording apparatus illustrated includes a transmitting circuit comprising a microphone *a* and a battery 2, connected in series with the input side 3*i* of a transformer or suitable amplifier 3. When it is desired to record light waves instead of sound waves, a photo-electric cell, not shown, may be employed in place of the microphone 2.

60 The recording or magnetic circuit is also a series circuit connected with the output side 3*o* of the transformer or suitable amplifier 3, and includes a plurality of electro-magnets 4 and 5, said magnets being spaced 65 apart and arranged to contact lightly with

the magnetizable body or wire 6 passing therebetween. The body 6 is subjected to magnets of different magnetic effect, and in the case illustrated, due to the series windings of the magnets 4 and 5, the magnetizable body is subjected to opposite polarities during its translation between the effective areas of the magnets.

In the form of Fig. 1, the flux densities of the magnets 4 and 5 are equal, but obviously the same may be made unequal when desired. To this end, in Fig. 2, I have shown the magnet 4*a* of smaller cross-section than the magnet 5, both magnets having the same number of magnetic turns and the same current passing through both, thereby producing unequal flux density.

Similarly, in Fig. 3, the same result is produced by providing the electro-magnet 5*a* with a greater number of magnetic turns than the magnet 4. And, further, in Fig. 4, a resistance *R* is placed in circuit with the magnet 5*b*, thereby dividing the total current in such a manner that only a portion thereof will pass through the magnetic windings of said magnet, thereby reducing the flux density therein.

In producing a record upon the magnetizable body 6, said body is translated by suitable means hereinafter more fully described, between the magnets 4 and 5. As stated supra, the magnets are in light contact only with the body or wire to obviate wear on the effective surfaces of said magnets and eliminate the "scratch" produced in previous methods.

Sound waves are transformed by means of the microphone transmitting circuit into magnetic impulses in the magnets 4 and 5, which impulses are recorded on the magnetizable body 6 to form a continuous record of said sound waves. This record is capable of being reproduced or re-transformed into sound waves by means of a somewhat similar apparatus.

In the step of reproducing, and as shown in Fig. 5, the magnetizable body or wire 6 passes between spaced-apart electro-magnets 7 and 8, the magnetic windings of which are in series with the input side 9*i* of a transformer or suitable amplifier 9. Said magnets are preferably of opposite polarity and serve to convert the magnetic record or impulses on the body 6 into an electric current in the transformer or amplifier 9.

In this instance, the electro-magnets 7 and 8 are not in intimate relation, or preferably not even in light contact with the body 6, but are on the verge of contact therewith, thus preventing the objectionable "scratching" during the reproduction step.

The output side 9*o* of the transformer or amplifier 9 is in turn connected in series with a reproducer or loud speaker 10, whereby the electric currents produced in the trans-

former 9 are reproduced into sound waves corresponding in quality and frequency with the waves transmitted and recorded by means of the apparatus in Fig. 1.

5 The recording apparatus shown in Fig. 1, and the reproducing apparatus of Fig. 5, may be positioned adjacent one another, as in Fig. 6. When so placed, the magnetizable body 6 is translated first between the electro-magnets 4 and 5 for receiving the magnetic record, and then passed between the electro-magnets 7 and 8 for reproducing the sound through the medium of the reproducer 10.

Under my method, it is possible to simultaneously record and reproduce a record, and in the form of Fig. 7 means are shown for effecting this result. As illustrated, the recording electro-magnets 4c and 5c, and the reproducing electro-magnets 7c and 8c are 15 arranged radially with respect to the magnetizable body 6. Said magnets 4c and 5c are connected as in Fig. 6 in a transmitting circuit, and magnets 7c and 8c in a reproducing circuit. Thus, the record may be applied 20 to the body or wire 6 by means of the magnets 4c and 5c having any of the characteristics shown in Figs. 1 to 4 inclusive, and simultaneously reproduced by means of the magnets 7c and 8c, preferably of opposite polarity.

Fig. 8 illustrates one form of means for translating the magnetizable body or wire in operative relation with respect to the magnetic circuits. C designates generally a magnetic circuit which may be either the recording or the reproducing circuit, or both.

The magnetizable body is wound upon two reels A and B, said reels being selectively rotatable by means of a motor M through suitable means, as for example, the belt drives shown, which operate to drive said reels through clutches, not shown. In the specific case shown, the reel A is being driven to translate the body 6 in the direction from B 45 to A in operative relation with respect to the magnets C. Reel B is not driven by the motor M in such case, but is braked by suitable friction means, not shown, to maintain the required tension in the body 6.

50 For the sake of simplicity, the drawings show only two magnets for recording and two for reproducing, a wire as the magnetizable body, a microphone for recording sound, and a loud speaker for reproducing sound; but a plurality of magnets for recording and for 55 reproducing, any desired form of magnetizable body, any suitable means for changing waves of any range of frequencies into electrical waves, and any suitable means for 60 changing electrical waves back into waves of any range of frequencies may be used, so that the invention may be applicable to recording and reproducing waves of any range of frequencies, such as sound waves or light waves, for example.

The system of magnets used for recording on a magnetizable body preferably consists of two or more electro-magnets, with a different flux density for each electro-magnet, for any instantaneous value of the energizing current. One or more of the cores of these 70 electro-magnets are in light contact with the magnetizable body.

Any suitable means may be employed to obtain a different flux density for each electro-magnet, such as cores of different materials, 75 windings with a different number of turns, windings in opposite directions, cores of unequal cross-section, different values of the energizing current, or any combination of the various variables which affect flux density. It is, however, of the utmost importance that one or more of the cores of these electro-magnets be in light contact with the magnetizable body, since if they are not in contact, the 80 electro-magnetic record on the body will not be precise and clearly defined, but will be distorted, while, if they are in too intimate a contact, the objectionable "wire scratch" will be recorded on the magnetizable body and 85 cannot be eliminated, except by means which will also remove certain frequencies which were present in the original matter recorded, thus resulting in a distorted reproduction.

According to the methods employed prior 90 to my invention, for recording on a magnetizable body, the core of the recording magnet has always been in intimate and close contact with the body to such a degree that a definite pressure exists between the core and the body. As a result of this contact under 95 pressure, a very definite friction exists between the core of the magnet and the body, as the latter is caused to move past the core, with the result that both the core and the body are subjected to a mutual rubbing action, and to more or less wear. When recording on a wire, for example, with this intimate contact between wire and magnet core, the wire is more or less deformed or 100 tends to be moved out of its straight line movement past the core. For this reason, a groove or recess is worn in the core, with the result that after a certain amount of use, the 105 core must be replaced by a new one.

The wire itself is also subjected to wear, with the result that its surface is slowly eroded and roughened, but what is more important, changes are set up which are made 110 evident in the reproduction by the presence in such reproduction of wave frequencies which were not present in the original matter from which the record was made.

In the case of records made by the method disclosed in the present invention, the cores 115 of the recording magnets are in light contact with the magnetizable body, that is, they are just barely in contact with it, and little or no pressure, and therefore friction, exists between them. As a result, there is very slight 120

wear of the magnet cores, their life is very long, and the wear of the magnetizable body is also reduced to a minimum, thus retaining a smooth surface as opposed to the roughened surface with other methods, and of most importance, the above-mentioned undesirable changes resulting in the addition of frequencies not present in the original matter, are avoided, thus resulting in a perfect record and reproduction.

The system of electro-magnets used for reproducing a record so made on a magnetizable body, consists of two or more magnets, in the windings of which currents of different instantaneous values are induced by the passage of any point of the magnetizable body past the poles of the magnets. One or more of the cores of these electro-magnets are on the verge of contact with the magnetizable body. The desired effect of induced currents in the windings of the magnets which are of different instantaneous values may be obtained in a variety of ways, by using any combination of the variables mentioned in the case of the magnetic system used for recording. In this case, however, none of the cores of the electro-magnets may be in contact with the body.

The important point is that one or more of the cores of these magnets be on the verge of contact with the magnetizable body, since, if they are in contact, the undesirable "wire scratch" will appear in the reproduction, while if they are moved too far away from the magnetizable body, the reproduction will not be clear cut, but will be distorted.

The same system of magnets as used for recording, may also be used for later reproduction, after the operation of recording has been completed. In this case, it will be necessary to move the cores of the magnets from the recording position where they are in light contact with the magnetizable body, to a position in which they are ready for reproduction and are on the verge of contact with the body. This movement of the cores of the electromagnets may be accomplished by any suitable means, as for instance, a micrometer screw which moves either the magnets and their cores or the cores alone.

The systems of electro-magnets used for recording and for reproducing may be the same system, as described above, or two separate systems, as shown in Fig. 6. In the event that two separate systems are used, one for recording and the other for reproduction, these two systems may be similar or may be unlike. I have found that I can use one system for recording and can obtain a satisfactory reproduction by the use of this same system or a similar system, of course, changing the position of the cores as described, using a light contact with the magnetizable body for recording and moving the cores to a position where they are on the

verge of contact with the body when reproducing.

For reproduction of a record so made, I can also use a system of electro-magnets, which is not similar to that used for recording, and with which I can obtain a satisfactory reproduction, but with which it is impossible to make a satisfactory record on the magnetizable body.

A record made and reproduced by the methods described in the invention can be retained indefinitely on the magnetizable body and can be reproduced as often as desired, without any change in the character of the reproduction. I have reproduced records so made thousands of times and have found that they are still in perfect condition after such repeated reproduction, which simulated the effect of several years use in a short period of time. This permanency of the record is impossible to achieve with other means for recording and reproduction which were known and used prior to this time.

I claim:

1. The method of recording and reproducing wave frequencies, which consists in first subjecting a magnetizable body to the action of a magnet connected to suitable means for varying the magnetization of the magnet in accordance with said wave frequencies and which is in light contact with the body, and then subjecting a magnet connected to suitable means for reproducing said wave frequencies and which is on the verge of contact with the body, to the action of the body.

2. The method of recording and reproducing wave frequencies, which consists in first subjecting a magnetizable body to the action of a plurality of magnetic poles of different flux densities, and then subjecting a plurality of magnetic poles, connected to suitable means for reproducing said wave frequencies and which are disposed on the verge of contact with said body, to the action of said body.

3. The method of recording and reproducing wave frequencies, which consists in first subjecting a magnetizable body to light contact with a plurality of magnetic poles of different flux densities connected to a common source of energizing current, and then subjecting a plurality of electro-magnetic poles, connected to suitable means for reproducing said wave frequencies and which are disposed on the verge of contact with said body, to the action of said body.

4. The method of recording and reproducing wave frequencies, which consists in subjecting a magnetizable body to the action of an electro-magnet connected to suitable means for varying the electric current flowing through the winding of the magnet in accordance with said wave frequencies and which is in light contact with said body for recording and simultaneously subjecting an electro-magnet, connected to suitable means for re-

producing said wave frequencies and which is on the verge of contact with said body, to the action of said body for reproducing, whereby to effect a simultaneous recording and reproducing.

5 5. A step in the method of recording and reproducing wave frequencies, which consists in subjecting a magnetizable body to light contact with a plurality of magnetic poles of different flux densities connected to a common source of energizing current.

10 6. A step in the method of recording and reproducing wave frequencies, which consists in subjecting a magnetizable body to light contact with a plurality of magnetic poles of different flux densities for any instantaneous value of energizing current.

15 7. A step in the method of recording and reproducing wave frequencies, which consists in subjecting a plurality of electro-magnetic poles which are on the verge of contact with a magnetizable body on which said wave frequencies have been previously recorded, and in the windings of which electric currents of different instantaneous values are induced, to

20 the action of said body.

8. The method of recording and reproducing wave frequencies, which consists in first subjecting a magnetizable body to light contact with a plurality of magnetic poles of different flux densities, and then subjecting a plurality of magnetic poles, connected to suitable means for reproducing said wave frequencies and which are disposed on the verge

25 of contact with the body, to the action of said body.

9. The method of recording and reproducing wave frequencies, which consists in first subjecting a magnetizable body to the action of a plurality of magnetic poles of different flux densities connected to a common source of energizing current, and then subjecting a plurality of electro-magnetic poles, connected to suitable means for reproducing said wave frequencies and which are disposed on the verge

30 of contact with said body, to the action of the body.

10. A step in the method of recording and reproducing wave frequencies, which consists in subjecting a magnetizable body to the action of a plurality of magnetic poles of different flux densities connected to suitable means for varying the magnetization of said poles in accordance with said wave frequencies.

35 11. A step in the method of recording and reproducing wave frequencies, which consists in subjecting a plurality of electro-magnetic poles in the windings of which electric currents of different instantaneous values are induced, to the action of a magnetizable body on which said wave frequencies have been previously recorded.

In testimony whereof I affix my signature.
65 RICHARD B. T. KILIANI.
